UNITED STATES PATENT OFFICE.

GUSTAF KELLGREN, OF EVERETT, MASSACHUSETTS.

LOAD-HANDLING APPARATUS.

1,243,074.

Specification of Letters Patent. Patented Oct. 16, 1917.

Application filed January 17, 1916. Serial No. 72,452.

To all whom it may concern:

Be it known that I, GUSTAF KELLGREN, a citizen of the United States, and a resident of Everett, county of Middlesex, and State 5 of Massachusetts, have invented an Improvement in Load-Handling Apparatus, of which the following description, in connection with the accompanying drawings, is a specification, like characters on the drawings representing like parts.

This invention relates to load handling apparatus, in general, and more particularly to dumping vehicles, and in certain aspects may be considered an improvement on the 15 apparatus disclosed in my co-pending earlier application, filed June 7, 1913 Patent No. 1,168,811, dated January 18, 1916.

The objects and features of the invention will be best understood from the following 20 description, taken in connection with the accompanying drawings, of a vehicle embodying one form of my invention selected for the purpose of illustration, it being understood that the invention in its true scope 25 is definitely set forth by the claims.

In the drawings:

Figure 1 is a side elevation of a dumping motor vehicle embodying one form of the invention;

30 Fig. 1^a shows an illustrative form of clutch mechanism for connecting and disconnecting the drive shaft of the motor with the hoisting or dumping mechanism.

Fig. 2 is a longitudinal sectional elevation on an enlarged scale of the right-hand portion of the vehicle shown in Fig. 1, illustrating more particularly the tilting or lifting mechanism with the body in its lowered position;

40 Fig. 3 is a longitudinal sectional elevation on an enlarged scale showing the lifting or tilting mechanism with the body in raised or tilted position;

Fig. 4 is a view on an enlarged scale of the 45 lifting or tilting mechanism viewed from the left of Fig. 3, certain parts being shown in section.

In the drawings, the invention is shown in its application to a dumping motor vehicle, but it will be apparent that as to certain of its features it is susceptible of a variety of other applications without departing from the spirit of the invention.

The chassis of the vehicle may be of any 55 usual suitable construction, including the usual longitudinally and transversely dis-

posed and spaced frame members. One of the side chassis members is shown at 2, in Fig. 1. The engine and drive shaft by which the vehicle is propelled and the clutch 60 by which the drive shaft may be disconnected from and connected to the crank shaft of the engine may be of any suitable and usual construction and mode of operation and will therefore not be described, they being in any 65 suitable location.

The fixed frame of the machine, rigidly secured in any suitable manner to the chassis, may be of any suitable and usual construction, said frame herein comprising 70 two side frame members fastened onto the longitudinal chassis side members, one of said side frame members being indicated in Fig. 1 by 12, secured to the chassis side member 2 by bolts 6, 6. To these members 12 are 75 secured transverse members 14, as by bolts 8. Upon these transverse members 14 are secured the fixed longitudinal side frame members 10, 10, by bolts or any other suitable fastening means. Mounted in suitable 80 bearings 17 upon the longitudinal side member 12 and transverse member 13, Fig. 1^a, is a transverse shaft 16 provided upon one end with a sprocket wheel 18. This transverse shaft will preferably be driven from the 85 drive shaft 20 of the vehicle through gears 22, 24 and suitable clutch comprising the clutch members 26, 28 and operating lever 30 therefor. All these parts may be of any suitable construction and mode of operation 90 and need not be herein more fully described. The sprocket wheel 18 drives a second sprocket wheel 32 through a sprocket chain 34, said second sprocket wheel 32 being mounted upon a stud shaft 36 journaled 95 in bearings provided on one of the longitudinal side frame members 10. Also mounted upon the stud shaft 36 is a drum 38 and a pinion 40 which latter meshes with a gear 42 mounted upon a stud shaft 44 journaled in a bracket 46 and said longitudinal side member 10, said bracket being secured to said side member in appropriately spaced relation thereto, in any suitable manner as by bolts 48, one of which is shown in Fig. 1. 100 A band brake 50 operated by a hand lever 52 may be provided to coöperate with the drum 38 to control the downward swinging movement of the body when the latter is lowered. Connected to the gear 42 and concentric therewith is a pinion 54 which meshes with a gear 56 mounted upon a shaft 105

58 extending transversely of the machine and journaled in suitable bearings 19 provided in the side frame members 10, 10. This shaft 58 forms part of the actual lifting or tilting mechanism which in the embodiment of the invention herein described for illustrative purposes may be constructed as follows. To points adjacent each end of said shaft 58 are secured traction members, herein chains 60, said chains extending toward the rear end of the machine, Fig. 2, where they pass under and around sheaves 62 mounted for free rotation in brackets 64 bolted to the rear or right-hand transverse frame member 14, viewing Fig. 2. After passing over said sheaves, the chains 60 extend toward the front of the machine and are connected at their front ends to the free ends of the levers 70, 70, preferably by turn-buckles 66 secured to a shaft 68 which joins the free ends of two lifting arms 70, 70, as shown in Fig. 4. The turn-buckles embrace the shaft 68 loosely enough to permit relative rotation of the rod and turn-buckles. Said lifting arms 70, 70 are pivoted at one end at 74 between the upturned wings of two angle iron 73, 75, bolted by their horizontal wings to one of the cross members 14, 14. Said arms 70, 70 carry rolls 76 at their free ends. Preferably, said lifting arms will be angular in shape, as clearly shown in Figs. 2 and 3, and will be joined at their elbow or angular portions by a transverse rod or shaft 78 upon the reduced end portions of which are preferably loosely mounted flanged rollers 80, between the arms 70, 70 and the shoulders formed on said shaft by said reduced end portions. The said reduced end portions extend through the arms 70, 70, which are mounted for free rotation thereon, and also support for free rotation, outside of said arms 70, 70 and spaced from the latter by washers 82, a second pair of shorter lifting arms 84. These lifting arms 84 are preferably also angular in shape and consist preferably each of two arm members. Between the two members forming each of the arms 84 there may be mounted for free rotation upon said shaft 78 a roller 83, see Fig. 2, similar in function to the rollers 76. Between the right-hand ends, viewing Fig. 2, of the two arm members forming each of the shorter lifting arms 84, is pivoted at 86 one end of an arm 88, the other ends of said arms 88 being pivoted respectively at 90 to two angle irons 92, 92, pivoted at their right-hand ends, Fig. 2, to the side frame members 10, respectively, at 94 and normally resting at their left-hand ends, Fig. 2, upon a transverse block 21, secured at both ends upon the frame members 12, 12 when the lifting mechanism is collapsed and the body 98 is in its horizontal or lowered position. In this position of the body the horizontal wings of the angle irons rest upon the upper edges of the frame members 10, 10, their vertical wings extending downwardly along the faces of said side members 10, 10. Shorter angle irons 95, 95 extend a certain distance along said angle irons 92, 92 and are secured by their vertical wings to the vertical wings of said angle irons 92 by flat-headed rivets 23, Fig. 4. The horizontal wings of said angle irons 95, 95 form guide rails for rollers 96, mounted in the free ends of the lifting arms 84, and for the rollers 76 of the longer arms 70, 70.

The long lifting arms 70 will preferably be braced, Fig. 4, by diagonally disposed bracing rods 100 and the traction members 60, when the body is in its lowered position, will preferably extend over the flanged rollers 80 located at the angle of said lifting arms as above described, in such manner that the section of the traction members extending between said rollers 80 and the free ends of the arms 70 shall pass in relatively close proximity to the axis of the rollers 96 mounted in the free ends of the shorter lifting arms 84.

It will be understood, of course, that the body 98 is secured to the longitudinal angle irons 92 in any suitable manner so as to tilt therewith.

The operation of the construction so far described is as follows: If the motor be started and the clutches connecting the transverse shaft 16 with the crank shaft of the motor be thrown in, the said shaft 16 will through the sprocket wheel 18, sprocket chain 34, sprocket wheel 32 and gears 40, 42, 54 and 56, rotate the shaft 58 and wind thereon the chains 60. At the beginning of this operation, the rollers 96 upon the free ends of the shorter lifting arms 84 are respectively in contact with the under sides of the horizontal portions of the angle irons 95 while the rollers 76 on the free ends of the longer lifting arms 70 are out of contact with said angle irons, as shown in Fig. 2. As the chains 60 are wound upon the shaft 58, the traction thus exerted on the free ends of the longer lifting arms 70 will swing said lifting arms upwardly about their pivots 74. This will raise the pivotal points 78 of the arms 70 and 84 and will thus cause the shorter lifting arms 84 also to swing upwardly about their lower ends, owing to the connection of said lower ends at 86 to the arms 88. The initial raising or tilting of the body 98 about its pivotal points 94 is thus effected by the more effective rollers 83, 83 and rollers 96, 96 on the shorter lifting arms 84, and as the traction members 60 extend in close proximity to the axis of the rollers 83 and 96, it will be seen that these rollers, that is to say, the points of application of the lifting force to the body are substantially on the straight line along which

the tractional force is exerted, said force being thus applied in the most effective manner and at the most effective point. As the shaft 58 continues to wind up the chains 60, the long arms 70 gradually swing upwardly by the rollers 96 of the arms 84, and the rollers 76 on the free ends of the arms 70 now themselves engage the lower surface of the horizontal portions of the angle irons 95—95 and continue the lifting action as the rollers 96 cease their lifting action. It will be seen that during the lifting action of the rollers 76, the tractional force is applied directly at said rollers, that is to say, at the 15 points where the arms 70 exert their lifting action on the body to be lifted. The lifting action may be continued until the desired inclination or elevation of the body has been attained when the motor may be stopped or 20 the clutch thrown out to arrest the body in the position desired. A pawl and ratchet may be provided on the shaft 40, for example, to maintain the body in its lifted position. When it is desired to lower the 25 body, this pawl is thrown out and the lowering movement controlled by the brake 52, as already described.

By making the angle of the shorter lifting arms 84 more acute so as to lower the 30 rollers 96 somewhat when the parts are assembled, the rollers 83 will exert the initial lifting action, the rollers 96 becoming operative later and finally the rollers 76.

It is sometimes desirable to raise the rear 35 end of the body as well as the forward end, but to a lesser degree, so as still to preserve a tilted position of the body toward the rear of the machine when the body has been raised to the desired height. As an instance 40 where it is convenient to raise the rear end of the body in this manner may be cited the case where it is necessary to use a chute to convey the material to be dumped from the body to the place where it is to be deposited, and it is necessary to use so long a 45 chute that the necessary inclination of the latter cannot be obtained. To meet such a contingency, the present invention may comprise means for raising the rear end of the 50 body in the manner referred to. To this end, an arm 102 may be pivoted at one end upon each of the pivots 90, 90, each arm 102 being provided at its free end with a roller 104. Adjacent the free end of each 55 of the arms 102 is pivoted at 108 the free end of a rod 106, and to the lower end portion of each of the rods 88, 88, is pivoted the free end of a rod 107, the rods 106, 107 being located one behind the other in a 60 horizontal plane, each rod 106 being provided with a collar 106' which embraces the coöoperating rod 107 and each rod 107 being provided with a collar 107' which embraces the coöoperating rod 106. A series of holes 65 may be provided in one of the rods 106, 107,

they being herein provided in the rod 106 for example, one such hole being shown at 111, Fig. 2, said holes being adapted to receive a locking pin of any suitable construction. The arms 102 may also be braced by 70 diagonal rods, not shown, extending from one to the other, substantially similar in arrangement to the rods 100 which act as braces for the lifting arms. The points of connection of these bracing rods to the arms 75 102 are shown at 110 in Figs. 2 and 3.

With the body of the vehicle in its lowered position, as shown in Fig. 2, the arms 102 occupy the position shown in said figure, and if no pin be inserted in the holes 111, then, as the lifting arms 70 swing upwardly in raising the front end of the body, the pivot 78 moves toward the rear of the machine and the lower ends of the arms 88, owing to their connection with the lower 80 ends of the arms 84 will be swung downwardly and toward the rear of the machine, thus simply causing the rods 106, 107 to telescope without moving the arms 102. But if a pin be inserted in the holes 111 of the rods 106, 107 while the body is still in lowered position, then the rods 106, 107 85 will be locked and cannot telescope, and as the lower end of the arms 88, 88 are moving toward the rear of the machine in the lifting operation, as above described, the two sets of rods 106, 107 will raise the arms 102, as shown in dotted lines, Fig. 3, and at a certain point in the lifting movement of the body, the rollers 104 on the free ends of 90 said arm 102 will thus come in contact with the under surface of the body proper 98 at each side and near the rear end thereof, and as, when this construction for raising the rear end of the body is used, said body is 95 not rigidly secured to the angle irons 92 but is merely pivoted thereto at its front end, as shown in Fig. 1, at 112, the body will, in the further lifting movement be 100 tilted upwardly about this pivotal connection 112, the elevation of the rear end of the body, however, being less than that of the forward end, so that the body will still 105 maintain a downwardly inclined position toward the rear of the machine, as shown in 110 dotted lines in Fig. 3.

If desired, hook-shaped braces 114 secured to the front transverse frame member 14 may be provided to embrace the shaft 58 intermediate its two end bars to give the 115 latter additional support against the strain exerted thereon by the traction members 60. The shaft 36 may have a squared end, as shown in Fig. 1, to enable the apparatus to be operated by hand if desired.

When the construction above described for lifting the rear end of the body is used, means will preferably be provided to steady the rear end of the body. This means may comprise guiding or stay members 116 se- 120 125 130

cured in any suitable manner, one to the outside of each of the side frame members 10 and projecting above the upper edge of the latter so as to embrace the rear end of 5 the bottom of the body between them when the rear end of the body is in its lowered position.

The lifting and tilting mechanism constructed in accordance with the present invention possesses many advantages over those heretofore used. Among other advantages, for example, it may be stated that the mechanism is extremely simple, not liable to get out of order, extremely rapid 15 in operation and secures a maximum lifting force with a minimum expenditure of power, extremely heavy loads being quickly and easily handled.

It will be apparent that it is not essential 20 that all the features of the invention be used conjointly, but that they might be used to advantage separately in various combinations and subcombinations. It will also be understood that, although described as embodied in the details illustrated, the invention is not to be understood as circumscribed by or limited to said details or any of them, but that the construction may be variously modified without departing from the true 25 scope of the invention which is definitely set forth by the claims.

Claims:

1. In a load handling apparatus, in combination, a suitable support; a load supporting body normally resting on said support; a pair of guide rails secured to said body; a pair of angular lifting arms, pivoted at one end for swinging movement; a roller mounted at the free end of each of said lifting arms and adapted to coöperate with said guide rails; a second pair of angular lifting arms, each arm of said pair being pivoted at one end for swinging movement upon said support; a roller mounted at the free end of 40 each of said second pair of lifting arms and adapted to coöperate with said guide rails; a pair of traction members operatively connected to one of said pairs of lifting arms; a shaft upon which said traction members 45 are adapted to be wound; and means to drive said shaft to wind said traction members thereon.

2. In a load handling apparatus, in combination, a suitable support; a frame pivoted 55 thereto and normally resting thereon; a body pivoted to said frame and normally resting on the latter; guide rails on said frame; a pair of lifting arms, each arm of said pair pivoted at one end upon said support; a 60 roller mounted at the free end of each one of the arms of said pair and adapted to coöperate with the guide rails on said frame; a second pair of lifting arms pivotally connected intermediate their ends to said first 65 pair of lifting arms; a pair of collapsible

members, each member of said pair having one end pivotally connected to one end of said second pair of lifting arms; means to prevent said members from collapsing; a roller mounted at the other end of each one 70 of said second pair of lifting arms and adapted to coöperate with said guide rails on said frame; a third pair of lifting arms; each arm of said pair having one end pivotally connected to said frame and the other end pivotally connected to the other end of one of said collapsible members; a roller mounted at the free end of each arm of said third pair of lifting arms and adapted to coöperate with said body; a pair of traction 80 members operatively connected to said first-named pair of lifting arms; a shaft upon which said traction members are adapted to be wound; and means to drive said shaft to wind said traction members thereon. 85

3. In a load handling apparatus, in combination, a suitable support; a load supporting body normally resting on said support; a pair of guide rails secured to said body; a pair of angular lifting arms, pivoted at one end for swinging movement; a roller mounted at the free end of each of said angular lifting arms and adapted to coöperate with said guide rails; a second pair of angular lifting arms, each arm of said pair being pivoted at one end upon said support; a roller mounted at the free end of each of said second pair of lifting arms and adapted to coöperate with said guide rails; a pair of traction members operatively connected to 100 one of said pairs of lifting arms; guide sheaves for said traction members; a shaft upon which said traction members are adapted to be wound; and means to drive said shaft to wind said traction members 105 thereon.

4. In a load handling apparatus, in combination, a suitable support; a tiltable load supporting body normally in lowered position on said support; a pair of guide rails secured to said body; a pair of angular lifting arms, pivoted at one end for swinging movement; a roller mounted at the free end of each of said lifting arms and adapted to coöperate with said guide rails; a second pair of angular lifting arms, each arm of said pair being longer than the arms of said first-named pair and pivoted at one end upon said support; a roller mounted at the free end of each of said second pair of lifting arms and adapted to coöperate with said guide rails; pivotal connection between said first-named pair and said second-named pair of lifting arms; traction members operatively connected to said lifting arms; a shaft upon which said traction members are adapted to be wound; and means to drive said shaft to wind said traction members thereon. 110 115 120 125

5. In a load handling apparatus, in combination,

- bination, a suitable support; a tiltable load supporting body normally in lowered position on said support; guide rails secured to said body; a plurality of relatively movable 5 angular lifting arms pivoted at one end for swinging movement; traction members operatively connected to said lifting arms; a second pair of angular arms each arm of said pair being longer than the arms of said 10 first named pair, and pivoted at one end upon said support, and adapted to coöperate with said guide rails; a shaft upon which said traction members are adapted to be wound; and means to drive said shaft to 15 wind said traction members thereon and cause said lifting arms to lift or tilt said body relatively to said support.
6. In a load handling apparatus, in combination, a suitable support; a frame pivotally connected to said support and normally resting thereon; a body pivotally connected to said frame and normally resting on the latter; angular lifting arms to coöperate with said frame to tilt the latter 25 about its pivotal connection with said support; further lifting arms adapted to coöperate with said body to tilt said body about its pivotal connection with said frame; connections between said angular frame lifting arms and said body lifting arms to operate the latter from the former; traction members and winding means therefor, said traction members extending, during a portion at least of the operation of said angular 30 lifting arms, from said winding means to the angle of said angular lifting arms and from said angle to the free ends of said angular lifting arms, to increase the effectiveness of said winding means.
- 40 7. In a dumping vehicle, in combination, a load carrying dumping body adapted to be tilted to dump its load; a suitable support for said load carrying dumping body; an angular body lifting arm pivoted at one 45 end for swinging movement; pivotal connections connecting one end of said angular body lifting arm to one of said two first-named parts; a second arm longer than the aforesaid arm and pivoted at one end upon 50 said support; anti-friction means through which said angular body lifting arm acts on the other of said two first-named parts to tilt said body; a traction member connected to said angular body lifting arm; and means 55 to operate said traction member to cause said angular body lifting arm to swing about its pivotal connection and to act through said anti-friction means to tilt said dumping body about its rear end relative to said support to dump its load, said traction member 60 being connected with the free end portion of said angular body lifting arm and extending, during a portion of the operation at least of said angular lifting arm, from its point of connection with said angular 65
- body lifting arm to the elbow of the latter and thence to said traction member operating means.
8. In a dumping vehicle, in combination, a load carrying dumping body adapted to be tilted to dump its load; a suitable support for said load carrying dumping body; an angular body lifting arm pivoted at one end for swinging movement; pivotal connections connecting one end of said angular body lifting arm to one of said two first-named parts; a second arm longer than the aforesaid arm and pivoted at one end upon said support; an anti-friction roller through which said angular body lifting arm acts on the other of said two first-named parts; a flexible traction member connected to said angular body lifting arm; and winding means for said traction member to cause the latter to swing said angular body lifting arm about its pivotal connection and cause it to act through said anti-friction roller to tilt said dumping body about its rear end relative to said support to dump its load, said flexible traction member being connected with the free end portion of said angular body lifting arm and extending, during a portion at least of the operation of said angular lifting arm, from its point of connection with said angular body lifting arm to the elbow of the latter and thence to said winding means.
9. In a dumping vehicle, in combination, a load carrying dumping body adapted to be tilted to dump its load; a suitable support for said load carrying dumping body; an angular body lifting member comprising two arms, one pivotally connected to one of said two first-named parts and the other coöperating, when said body lifting member is actuated, with the other of said two first-named parts to raise the forepart of said body; a traction member connected with the unpivoted arm of said body lifting member; means to operate said traction member and actuate said body lifting member to raise the forepart of said load carrying dumping body to dump its load, said traction member extending, during a portion at least of the operation of said body lifting member, from its connection with said unpivoted arm of said body lifting member substantially longitudinally of said arm to the junction of the two arms of said body lifting member and thence to said traction member operating means; means, operated by said angular lifting member, to raise the rear part of said body; and provision for rendering said rear part lifting mechanism operative or inoperative at will.
10. In a dumping vehicle, in combination, a load carrying dumping body adapted to be tilted to dump its load; a suitable support for said load carrying dumping body; a two-armed angular body lifting member, having

- one arm pivotally connected to one of said two first-named parts and the other, longer arm to coöperate with the other of said two first-named parts to raise the forepart of
- 5 said body, when said angular lifting member is actuated; a traction member connected to said longer arm of said angular lifting member; means to operate said traction member to actuate said angular lifting member and
- 10 rear part raising mechanism, said traction member extending, during a portion at least of the operation of said angular lifting member, longitudinally of the longer arm of said angular lifting member from its connection with said arm to the junction of the two arms of said angular lifting member and thence to the traction member operating means; and means to render said rear part raising mechanism operative or inoperative
- 15 at will.
11. In a dumping vehicle, in combination, a load carrying dumping body adapted to be tilted to dump its load; a suitable support for said load carrying dumping body; angular lifting arms 70 pivotally connected at one end to one of said two first-named parts and adapted to swing about said pivotal connections and act through anti-friction rollers 76 upon the other of said two first-named parts to raise the forepart of said body; further angular lifting arms 84 pivotally connected intermediate their ends to said first-named angular lifting arms 70 and connected at one of their ends to one of said two first-named parts, said angular lifting arms 84 being adapted to swing about their connections to act upon the other of said two first-named parts through anti-friction rollers 96 to raise the forepart of said body; traction members 60 and winding means therefor, said traction members being connected to the free ends of said angular lifting arms 70 and extending, during a portion at least of the operation of said angular lifting arms, from their point of connection therewith to the angle of said angular lifting arms and thence to said winding means; rear part lifting arms 102; and means connecting said rear part lifting arms with said forepart lifting arms to cause the former to be operated by the latter.
12. In a dumping vehicle, in combination, a load carrying dumping body adapted to be tilted to dump its load; a suitable support for said load carrying dumping body; angular lifting arms 70 pivotally connected at one end of one of said two first-named parts and adapted to swing about said pivotal connections and act through anti-friction rollers 76 upon the other of said two first-named parts to raise the forepart of said body; further angular lifting arms 84 pivotally connected intermediate their ends to said first-named angular lifting arms 70 and connected at one of their ends to one of said two first-named parts, said angular lifting arms 84 being adapted to swing about their connections to act upon the other of said two first-named parts through anti-friction rollers 96 to raise the forepart of said body; traction members 60 and winding means therefor, said traction members being connected to the free ends of said angular lifting arms 70 and extending, during a portion at least of the operation of said angular lifting arms, from their point of connection therewith to the angle of said angular lifting arms and thence to said winding means; rear part lifting arms 102; means connecting said rear part lifting arms with said forepart lifting arms to cause the former to be operated by the latter; and means to render said connections operative or inoperative at will.
13. In a dumping vehicle, in combination, a load carrying dumping body adapted to be tilted to dump its load; a suitable support for said load carrying dumping body; angular lifting arms 70 pivotally connected at one end to one of said two first-named parts and adapted to swing about their pivotal connections and act through anti-friction rollers 76 upon the other of said two first-named parts to raise the forepart of said body; traction members 60 and winding means therefor, said traction members being connected with the free ends of said angular lifting arms and extending, during a portion at least of the operation of said angular lifting arms, from their point of connection therewith to the angle of the arms and thence to said winding means; rear part lifting arms 102; means connecting said rear part lifting arms with said forepart lifting arms to cause the former to be operated by the latter; and means to render said connections operative or inoperative at will.
14. In testimony whereof, I have signed my name to this specification, in the presence of two subscribing witnesses.
